ICE SKATE SCABBARD

Filed March 31, 1930

Inventor:
Alfred Johnson,
By Cheever, Cox & Moore atty.

UNITED STATES PATENT OFFICE

ALFRED JOHNSON, OF CHICAGO, ILLINOIS

ICE-SKATE SCABBARD

Application filed March 31, 1930. Serial No. 440,192.

My invention relates to scabbards for the runners of ice skates.

One of the objects of my invention is to provide a scabbard which is quickly and easily attachable to the runner of the skate and which, when so attached, is firmly held in position thereon.

Another object of my invention resides in providing a cheap type of ice skate scabbard.

Still another object of my invention resides in providing such a scabbard provided with fastening means for holding the scabbard to the runner of the ice skate and in such a manner as not to mar the runner of the

skate.

Still another object of my invention resides in the economical manner in which the toe portion of the scabbard is formed from sheet material, such for instance as leather.

These and other objects of my invention will be apparent from a perusal of the following specification when taken in connection with the accompanying drawings, wherein:

Figure 1 is a side view of an ice skate with my improved scabbard attached to the runner;

Figure 2 is a perspective view of the scabbard alone;

Figure 3 is a view of the front portion of the scabbard and the spacing insert;

Figure 4 is a view taken through line 4—4 of Figure 1;

Figure 5 is a top view of the scabbard clip shown gripping over the top of the tubular runner mounting;

Figure 6 is a perspective view of a clip such as I use on my scabbard, but which is provided with some sort of covering to prevent abrading the metal of the runner, and

Figure 7 is a cross-sectional view corresponding to that shown in Figure 4 of my improved scabbard in position on a skate runner of different design from that shown in Figure 4.

Referring now to the drawings in detail, my improved scabbard 2 is preferably formed from a blank of sheet material. I prefer to use leather since it is more durable. The leather is cut and folded to provide the op-

posed sides 4 and 6 forming the longitudinal pocket or sheath for the skate runner 8. At the rear portion, the two lateral sides 4 and 6 of the leather are riveted together by means of the rivet or other fastening member 10. At the front, the lateral sides 4 and 6 of the scabbard are enlarged to provide two spaced apart nose portions 12 and 14 and at the bottom of these nose portions, the leather terminates as at 16. For the purpose of saving material in the construction of my scabbard, and to provide a simple and economical construction, and further for the purpose of adequately spacing apart the sides 4 and 6 of the scabbard, I provide an insert in the form

of a substantially V-shaped washer 18, which in the present instance may be formed of leather like the body of the scabbard. Obviously, the body of the scabbard may be formed of other material and this spacer may be formed of another material. The spacer 18 at its bottom portion terminates in a shoulder 20 and in a wedge-shaped tongue 22 which tongue 22 is adapted to overlie or rest upon the bottom wall 24 of the inside bottom wall of the scabbard, and the shoulder 20 is adapted to abut the shoulder 16. As thus positioned, the insert washer 18 lies between the two marginal curved edges of the tongue portions 12 and 14 of the front portion of the scabbard. Either stitchings or rivets 26 are then passed through the two front faces 12 and 14 of the scabbard and through the curved spacing member 18, thus integrally uniting the front portions of the scabbard and providing a permanent pocket for the runner.

The upper portion of the upper curved wall of the front portion of the scabbard overhangs or overlies the pocket so as to receive therebeneath the front portion of the runner of the skate, as clearly shown in the dotted lines in Figure 1.

In order to hold the scabbard in position on the runner, I provide the rear portion of the scabbard with a preferably spring metal clip 28 which may be fastened to the sides of the scabbard as by means of rivets 30.

Obviously any other desired means may be used for fastening this spring clip in position. The spring clip has inwardly project-

ing spring gripping jaws 32 and 34, which, as shown in Figure 4, frictionally grip over the tubular runner support 36, whereby to hold the scabbard securely in position on the 5 skate and yet will permit of the quick detachment of the scabbard. Figure 7 of the drawings illustrates the manner in which this spring metal clip is adapted to grip the skate runner of another type of skate. It will be 10 noted that the spring metal clip has the upper portions thereof permanently bent or deflected inwardly with the free edges thereof bent slightly outwardly, thereby providing the firm gripping effect.

15 In Figure 6, I have shown a slight modification of my spring clip. In this instance, the metal of the clip is provided with a coating or facing 38 to prevent the metal of the clip from marring, scratching, or de-facing 20 the runner or tubular runner support of the skate. This may be made of leather composition material, fabric, any type of sheet metal, suitably cemented to the walls of the spring clip.

25 It will thus be apparent that I have provided a very economical type of scabbard which may be quickly placed on the skate runner and which will firmly grip the runner; that the scabbard is formed of durable material, cheaply constructed to provide a 30 very rugged and serviceable scabbard.

Having thus described my invention, what I claim as new and desire to secure by Letters Patent is:

35 1. A scabbard for ice skates composed of sheet material formed to provide a longitudinal seat with upstanding sides for the runner of the skate, the forward portion of said seat having an overhanging closed end 40 and a spring clip permanently mounted on the outside of the upstanding sides of the scabbard with the bowed portion of the clip enclosing the part of the scabbard forming the longitudinal seat, said clip having free 45 inturned ends extending above the upstanding sides of the scabbard to provide a frictional fastening clasp to engage a portion of the skate.

50 2. A leather scabbard for an ice skate consisting of a single piece of leather folded upon itself to provide parallel sides, the rear end of said folded sides being fastened together, the front end of said sides being enlarged to provide an upwardly curved extending overhanging portion adapted to 55 overlie the front edge of the runner, fastening means for closing the front end portion of the sides and a spring clip permanently mounted on the outside of the rearward portion of said scabbard, the bowed portion of the clip enclosing the closed folded portion 60 of the leather, and the free inturned ends of the spring clip extending upwardly to provide a frictional fastening clasp to engage a portion of the 65 skate.

3. A skate scabbard consisting of a single piece of sheet material of greater length than the runner of a skate folded upon itself to provide a runner pocket, the rearmost folded sides being fastened together, the front of 70 said sides being cut away a short distance to the rear of the front and at the bottom of the folded portion to provide a shoulder, said front of the side portions being enlarged and extending upwardly to provide portions adapted to overhang the runner pocket formed between the sides, a spacing member of substantially C formation constructed to provide a cooperative shoulder to abut against the first mentioned shoulder, said spacing member being inserted between the two marginal edges of the front of the sides, and fastening means passing through the marginal edges of said sides and said spacing member, and a spring clip carried by the rear portion of said scabbards, said clip having its free ends extending upwardly.

4. A skate scabbard for ice skates having a runner pocket and having a spring metal clip for detachably connecting the scabbard to the skate, said spring metal clip being covered with material adapted to prevent 80 injury to the face of the skate.

5. A skate scabbard formed of a single piece of sheet material of length greater than the skate runner folded upon itself to provide a closed bottom and upstanding sides forming therebetween a runner pocket, a rivet passing through the rearmost portion of the upstanding walls of the scabbard to close the same, the front upstanding walls of the scabbard being cut away at the bottom directly at the folded joint to provide a shoulder, said upstanding walls being formed to curve forwardly and upwardly to provide an overhanging portion, a spacing insert of substantially C formation having its bottom portion arranged in a wedge-like taper with an adjacent under shoulder disposed between the front enlarged portions of the side members with the shoulder of the C portion abutting the shoulder of the scabbard, and rivets passing through the marginal curved portions of the front of the sides and through said spacing member to close the forward end of the scabbard, and a spring clip having the bowed portion straddling the rearward portion of the scabbard and riveted thereto at the sides, the free ends of the spring clip extending upwardly of the scabbard.

6. A scabbard for ice skates composed of sheet material formed to provide a longitudinal seat with upstanding sides for the runner of the skate, the front end of the scabbard having a portion overlying said runner, and a spring clip carried by the rearward portion of the scabbard, said clip having relatively long and resilient side members lying parallel to and fitting the upstanding walls of the scabbard, said upstanding walls

of the clip extending well above the up-standing walls of the scabbard and being bent inwardly so as to clip and overlie the top of the skate runner to hold the scabbard in position thereon.

5 In witness whereof, I have hereunto subscribed my name.

ALFRED JOHNSON.
